UNITED STATES PATENT OFFICE.

CHARLES P. DAY, OF EAST ORANGE, NEW JERSEY, ASSIGNOR TO DAY-ELDER, INC., A CORPORATION OF NEW JERSEY.

OIL BURNER.

Application filed February 25, 1924. Serial No. 694,917.

This invention relates more particularly to oil burners for use in connection with the furnaces or heaters of dwelling houses and the like, so as to do away with coal and employ the lighter grades of fuel oil in place of the same. I shall therefore describe my invention in connection with such a burner, although I desire it understood that the invention or any part thereof can be employed 5 in any kind of a burner to which it may be found applicable without departing from the spirit and scope of my invention.

The objects of the invention are to secure a construction of burner which shall obtain 15 a very effective vaporization of oil fed at a low pressure, as by gravity feed; to secure a very effective mixture of air with the vaporized oil, so that a strong hot flame is obtained; to enable the supply of such air to 20 be conveniently and closely regulated so as to secure maximum heat; to provide an improved construction not only for such regulation of air but for the vaporization of the oil and indeed for the entire burner; to enable the burner to be simply and inexpensively manufactured and assembled, as well as 25 taken apart for examination or repairs, and to obtain other advantages and results as may be brought out by the following description.

Referring to the accompanying drawings, in which the same numerals of reference indicate corresponding and like parts,

Figure 1 is a vertical central section of 35 one form of my improved burner;

Figure 2 is a side elevation partly in vertical central section and showing the vaporizing member about to be assembled with the other parts;

Figure 3 is a partial section on line 3-3 of Fig. 1;

Figure 4 is a section on line 4-4 of Fig. 1;

Figure 5 is a side elevation of the lower 45 part of the burner;

Figure 6 illustrates a modified form of control for the air supply and is a view in vertical section on line 6-6 of Figure 7 except that the lower central part of the burner is in side elevation with two of its supporting arms broken, and

Figure 7 is a similar section taken at right angles to that of Fig. 6.

In the specific embodiment of the inven-

tion shown in Figures 1-5 inclusive, 1 indicates the annular base portion of the main casting of my improved burner, said annular base portion being adapted to stand directly on the grate of a furnace the bars of which are indicated at 2, 2, Fig. 1, and 55 the entire grate outside and around the burner being covered, as by sheet material 3, so as to direct the enfire intake or draft of air upward through the annular base portion 1. Said annular base portion 1 has at 60 its upper part inwardly projecting webs 4 and 5 which serve to support a central portion around which the air draft may pass upward, said central portion providing a peripheral trough 6 and having at its center 65 an upwardly extending burner portion 7. This burner portion has a reduced upper part 8 which is closed at its top, and a central fuel supply pipe 9 is screwed into the 70 underside of said closed top and a burner tube 10 screwed into said closed top from the upper side, so that a continuous duct therethrough is furnished for the oil. A vaporizing member 11 has a lower tubular 75 end 12 which sets down over the upper reduced part 8 of the burner portion, and forms at its upper part a flattened cylindrical vaporizing chamber 13 into which the burner tube projects. Space is provided 80 around said burner tube in the bottom of the vaporizing chamber 12, and space is also provided between the bottom of said vaporizing chamber and the top of the upper part 8 of the burner portion, as well as 85 between the outer wall of said part 8 and the inner wall of the lower tubular end 12 of the vaporizing member. The shoulder formed by reducing the upper part 8 of the burner portion 7 is provided with a seat 14 to receive the lower end of the tubular lower portion 12 of the vaporizing member, and the end edge of said tubular portion 12 is notched, as most clearly shown at 15 in Fig. 90 2, so as to provide an annular series of apertures.

Extending upward from the annular base portion 1 is an annular casing 16 which preferably contracts inwardly over the trough 6 and receives at its upper edge a flaring section 17. Preferably this flaring section 17 of the casing extends from about the level of the reduction of the burner portion 7 to form its upper part 8, up to the 95 100 105

level of the vaporizing member 11, although it may extend either higher or lower at both its top and bottom, as may be found desirable.

- 5 The burner tube 10 is preferably branched at its upper end, so that oil supplied through the tube 9 drips from the open ends of the branches 18, 18 onto the floor of the vaporizing chamber 13 at a plurality of points.
- 10 Said floor is preferably elevated slightly at the center, and, in starting the burner, as the oil rises above said elevation it flows through the aperture around the burner tube and falling onto the top of the upper part 15 8 of the burner portion 7 passes downward between said upper part 8 and the tubular lower portion 12 of the vaporizing member and escapes through the notches in the lower end of said portion 12. The oil then falls 20 into the trough 6, and in starting the burner it is ignited in said trough 6 as by a match. Preferably, the trough 6 is provided with an overflow outlet of any suitable construction, the one I have shown being a pipe 19 leading 25 upward through the grate and being screwed into the widened web 5, said web being drilled as at 20 to afford communication with the trough 6 at the desired height. The flame from the oil burning in the trough 30 6 is directed upward by the casing sections 16, 17 and quickly heats the entire upper part of the burner, including the vaporizing member 11, so that the oil therein is vaporized and oil no longer flows down to the 35 trough 6 but vapor escapes at the lower notched end of the tubular portion 12 of the vaporizing member and burns from there in an upwardly-directed outwardly-flaring annular flame. Indeed, before the vaporizing 40 begins, it may be that the escaping oil has been burning from the same ignition openings at the junction of the tubular lower end of the vaporizing member with the burner support; obviously this depends entirely 45 on the amount of oil which has escaped before the match is applied, and is immaterial.

With the T-shaped burner tube 10 which I have shown, obviously the aperture through the floor of the vaporizing chamber 50 13 must be elongated, as shown in Fig. 4, in order to assemble the vaporizing member into its place, and so as to enable said vaporizing member to be accurately turned with said elongated aperture 21 transverse 55 to the T-head, I supply some outside indicating means such as ribs 22, 22 on opposite sides of the burner portion 7 and other ribs 23, 23 on the top of the vaporizing member 11 which when brought into vertical 60 plane of the ribs 22, 22 ensure that the aperture 21 and burner tube T-head are in proper transverse relation.

Preferably, the vapor discharge orifices are accurately determined by forming at the junction of the burner portion 7 and its up-

per reduced part 8 an upwardly projecting annular rib 24 into the inner edge of which the seat 14 can be machined, so that when the extremities of the teeth formed by the notches 15, see Fig. 2, are correspondingly machined, as at 25, the position of the vaporizing member will be accurately centered and the size of the discharge orifices accurately determined.

The air entering the burner from beneath 75 is prevented from passing into the central part of the burner by a closure plate 26, and if desired, the central closed chamber of the burner thus formed may be filled with any heat insulating material (not shown). The 80 entering air thus passes upwardly around said central portion of the burner, between it and the casing 16, and is preferably regulated by some means for varying the passage 85 between the top of the flange 27 around the trough 6 and the inwardly curved top 28 of the casing 16. In Figures 1-5 inclusive, I have shown this accomplished by means for moving the casing 16 up and down, the 90 annular base portion 1 being for this purpose provided with an exterior shoulder 29 upon which the lower edge of the casing 16 rests. Both said shoulder and lower edge of the casing are then provided with teeth 30 on the base 1 and 31 on the casing 16, said teeth having long inclines circumferentially of the burner, as shown in Fig. 5. By this construction, if the casing is turned to the left-hand in Fig. 5, obviously it rises with 95 respect to the annular base 1, and by looking at Figure 1 it will be seen that this will increase the annular air passage between the top of the casing 28 and the top of the flange 27. Such space can therefore be regulated 100 at will to control the air supply through the burner, and more particularly as to its velocity, the volume being controlled in the usual way by the furnace dampers and 105 drafts.

In Figures 6 and 7 I have shown another 110 means for controlling the air supply, the casing 32 being fixed as to vertical movement with respect to the annular base 33, and the lower part 34 of the burner portion, which has the trough 35, being provided 115 with an exterior sleeve 36 which can be slid up and down to vary the annular air passage between the top of said sleeve and the top 37 of the inside of the casing 32. Obviously, the sleeve 36 could be moved up and down in a variety of ways, but I have shown it provided with forked extensions 38 each of which straddles one of the webs 39 which extend between the annular base portion 33 and the lower part 34 of the central portion of the burner. These extensions 38 support and guide the sleeve 36, and to move it up and down it is provided with diametrically opposite downwardly extending 125 lugs 40, each of which is pivoted as by 130

5 a pin 41 to the slotted and bifurcated end of an arm 42 on a rocker shaft 43 extending across the annular base portion 33 and journaled at its opposite ends in the wall thereof. From a convenient portion of said shaft 43 and which I have shown as intermediate the arms 42, 42, an operating arm 44 extends downward and is pivotally connected to a connecting rod 45 shown as extending to the usual hinged air draft 46 at the base of the furnace wall 47. This air draft 46 is shown having a link 48 by which it may be automatically operated by any well-known thermostatic control (not shown). The pin 49 by which the operating arm 44 is pivoted to the connecting rod 45 preferably works in a slot 50, so that the air draft 46 may move to a certain extent independently of the burner sleeve 36; a 10 stop screw 51 working longitudinally of said slot 50 to vary the extent of such independent movement. By the means described, or other suitably equivalent means, the draft or passage of air through my improved burner may be automatically regulated from any well-known thermostatic control apparatus.

15 It will be understood that various detail changes and modifications may be made in my improved burner without departing from the spirit and scope of the invention, and therefore I do not wish to be understood as limiting myself except as required by the following claims when construed in the light of the prior art.

Having thus described the invention, what I claim is:

1. In a burner of the character described, an upwardly projecting cylindrical central portion having a flattened top, a horizontally disposed circular vaporizing chamber above said central portion forming with the top thereof a horizontally disposed radially expanding vapor passage and having a lower tubular portion forming with the sides of said central portion a downward cylindric annular continuation of said vapor passage, said vaporizing chamber having a central opening into said vapor passage and said vapor passage terminating in a vapor discharge, and means for supplying oil to said vaporizing chamber.

2. In a burner of the character described, an upwardly projecting cylindrical central portion having a flattened top, a horizontally disposed circular vaporizing chamber above said central portion forming with the top thereof a horizontally disposed radially expanding vapor passage and having a lower tubular portion forming with the sides of said central portion a downward cylindric annular continuation of said vapor passage, said vaporizing chamber having a central opening into said vapor discharge, means for supplying oil to said vaporizing

chamber, and means for seating said vaporizing chamber and its said lower tubular portion on said central portion by gravity.

3. In a burner of the character described, an upwardly projecting cylindrical central portion having a flattened top, a horizontally disposed circular vaporizing chamber above said central portion forming with the top thereof a horizontally disposed radially expanding vapor passage and having a lower tubular portion forming with the sides of said central portion a downward cylindric annular continuation of said vapor passage, said vaporizing chamber having a central opening into said vapor passage and said vapor passage terminating in a vapor discharge, means for supplying oil to said vaporizing chamber, and means for positioning said vaporizing chamber and its said lower tubular portion on said central portion so as to be separate therefrom and capable of being lifted upwardly off the same.

4. In a burner of the character described, an upper horizontally disposed circular vaporizing chamber with a central outlet in its floor, means for supplying oil to said vaporizing chamber at the side of said outlet, a vapor passage having a horizontally disposed radially expanding portion at the bottom of said vaporizing chamber and communicating with the outlet thereof and a cylindric annular portion leading downward from the outer edge of the first-mentioned portion, and means for discharging vapor from the lower end of said cylindric portion.

5. In a burner of the character described, an upwardly projecting cylindrical central portion having a flattened top and a peripheral shoulder below said top, a horizontally disposed circular vaporizing chamber above said central portion forming with the top thereof a horizontally disposed radially expanding vapor passage and having a lower tubular portion forming with the sides of said central portion a downward cylindric annular continuation of said vapor passage, said vaporizing chamber having a central opening into said vapor passage and its lower tubular portion forming a vapor discharge with the said shoulder of the central portion, and means for supplying oil to said vaporizing chamber.

6. In a burner of the character described, an upwardly projecting cylindrical central portion having a flattened top and an exterior shoulder with an upwardly projecting rib, a horizontally disposed circular vaporizing chamber above said central portion forming with the top thereof a horizontally disposed radially expanding vapor passage and having a lower tubular portion forming with the sides of said central portion a downward cylindric annular con-

tinuation of said vapor passage, said vaporizing chamber having a central opening into said vapor passage and its lower tubular portion seating on said shoulder in engagement with said rib to position the parts and form thereat a vapor outlet, and means for supplying oil to said vaporizing chamber.

7. In a burner of the character described, an upwardly projecting cylindrical central portion having a flattened top and an exterior shoulder with an upwardly projecting rib, a horizontally disposed circular vaporizing chamber above said central portion forming with the top thereof a horizontally disposed radially expanding vapor passage and having a lower tubular portion forming with the sides of said central portion a downward cylindric annular continuation of said vapor passage, said vaporizing chamber having a central opening into said vapor passage and said lower tubular portion at its lower end having its wall notched and the inner edge of said rib and the outer edge of the notched lower end being recessed to fit together and position the parts and form an annular series of vapor discharge outlets, and means for supplying oil to said vaporizing chamber.

8. In a burner, the combination with a vaporizing member providing a chamber having an elongated aperture in its floor, of an oil tube extending through said aperture and having a T-head adapted to discharge oil on said floor of the vaporizing chamber at both sides of said aperture, and a burner body portion supporting said oil tube and forming with the vaporizing member a passage leading from said aperture in the floor of the vaporizing chamber to a discharge outlet.

9. In a burner of the character described, a central burner portion providing a peripheral shoulder, an upper vaporizing portion having an elongated outlet in its floor and a tubular lower part adapted to enclose the upper part of said central portion and rotatably engage said shoulder to position said parts, said vaporizing portion being separate from said central portion and removable upwardly therefrom, and an oil tube extending upwardly through said central portion and floor of the vaporizing portion and having a lateral branch to discharge oil on the floor of said vaporizing member at one side of said aperture and prevent removal of said vaporizing member until its outlet is in alinement therewith.

10. In a burner, the combination of an annular base portion and a central burner portion having an enlarged bottom providing an annular space between itself and said base portion, an air-directing casing on said base portion extending upwardly and inwardly over said bottom of the cen-

tral portion, and means for varying the height of the opening between said casing and bottom of the central portion.

11. In a burner, the combination of an annular base portion and a central burner portion having an enlarged bottom providing an annular space between itself and said base portion, an air-directing casing on said base portion extending upwardly and inwardly over the bottom of the central portion, and means for raising and lowering said casing with respect to the central burner portion.

12. In a burner, the combination of an annular base portion and a central burner portion having an enlarged bottom providing an annular space between itself and said base portion, and an air-directing casing on said base portion extending upwardly and inwardly over said bottom of the central portion, said annular base and casing having cooperative engaging means whereby turning of the casing in one direction lowers it with respect to the central portion and turning it in the other direction raises it.

13. In a burner, the combination of an annular base portion and a central burner portion having an enlarged bottom providing an annular space between itself and said base portion, and an air-directing casing on said base portion extending upwardly and inwardly over said bottom of the central portion, said annular base and casing having at their meeting edges circumferentially elongated inclined teeth adapted to mesh with each other to lower the casing and to be turned out of mesh to raise the casing.

14. In a burner, the combination of an annular base portion and a central burner portion having an enlarged bottom providing an annular space between itself and said base portion, an air-directing casing on said base portion extending upwardly and inwardly over said bottom of the central portion, and cooperating means on said casing and annular base portion for varying the height of the opening between the central portion and said casing.

15. In a burner of the character described, an annular base and a central cylindrical burner portion in fixed relation to each other and providing between themselves an annular passage for an up-draft of air, said central burner portion having a reduced upper end, an upper vaporizing portion having a laterally projecting upper part and a cylindrical lower part telescoping the upper reduced end of the central burner portion and forming at its lower end with said central portion vapor discharge openings at the inner side of the annular up-draft of air and beneath said laterally projecting upper part of the vaporizing portion, and a peripheral air-directing casing seated on said base and flaring upwardly outward around said

vaporizing portion from the level of said vapor discharge openings.

16. In a burner of the character described, an annular base and a central cylindrical burner portion in fixed relation to each other and providing between themselves an annular passage for an up-draft of air, said central burner portion having a reduced upper end, an upper vaporizing portion having a laterally projecting upper part and a cylindrical lower part telescoping the upper reduced end of the central burner portion and forming at its lower end with said central portion vapor discharge openings at the inner side of the annular up-draft of air and beneath said laterally projecting upper part of the vaporizing portion, and a peripheral air-directing casing seated on the burner base and forming with the central cylindrical burner portion below the vapor discharge openings an annular air passage which extends outward further than the laterally projecting upper part of the vapor-

izing portion, said air-directing casing having an upper part which flares upwardly 25 outward around said vaporizing portion above the level of the vapor discharge openings.

17. In a burner of the character described, an annular base and a central burner portion 30 in fixed relation to each other and providing between themselves a passage for an up-draft of air, an upper vaporizing portion on said central portion and projecting laterally therefrom, said vaporizing portion having a 35 tubular lower part forming with said central portion a vapor passage with discharge openings at its lower end, and a peripheral air-directing casing on said base divided at substantially the level of said discharge 40 openings and having both its upper and lower portions seated by gravity and removable upwardly outside said vaporizing portion and independent thereof.

CHARLES P. DAY.
